The ornamental design for a vertical full-year calendar, as shown and described.

DESCRIPTION

FIG. 1 is a front view of a new design for a vertical full-year calendar;

FIG. 2 is a first partial front view thereof;

FIG. 3 is a second partial front view thereof;

FIG. 4 is a front view of a new design for an additional embodiment of a vertical full-year calendar;

FIG. 5 is a first partial front view thereof; and,

FIG. 6 is a second partial front view thereof.

The left, right, bottom, top, and rear views are not ornamental and have been omitted.

In FIGS. 1–3, solid gray scale shading is used to represent color contrast.

The broken lines shown in the drawings depict portions of the vertical full-year calendar that form no part of the claimed design.
